(57) **CLAIM**

The ornamental design for "jewelry medallion," as shown and described.

DESCRIPTION

FIG. 1 is a top plan view of a jewelry medallion showing my new design;

FIG. 2 is a right side elevational view thereof;

FIG. 3 is a front elevational view thereof; and,

FIG. 4 is a bottom plan view thereof.

The broken lines shown in the drawings illustrate environmental matter and portions of the jewelry medallion and form no part of the claimed design.
